(57) **CLAIM**

The ornamental design for universal cord grip, as shown and described.

DESCRIPTION

FIG. 1 is a front elevational view the invention;
FIG. 2 is a right side elevational view of the invention shown in FIG. 1;

FIG. 3 is a left side elevational view on the invention as shown in FIG. 1;

FIG. 4 is a rear elevational view of the invention as shown in FIG. 1;

FIG. 5 is a top plan view of the invention as shown in FIG. 1;

FIG. 6 is a bottom plan view of the invention as shown in FIG. 1; and,

FIG. 7 is a perspective view of the invention.

The broken line environmental showing is for illustrative purposes only and forms no part of the claimed design.
